UNITED STATES PATENT OFFICE

145,377

DESIGN FOR A CLOTHESPIN OR THE LIKE

Harry M. Broadwell, Bristol, Conn.

Application January 19, 1946, Serial No. 125,732

Term of patent 14 years

(Cl. D17—6)

To all whom it may concern:

Be it known that I, Harry M. Broadwell, a citizen of the United States, residing at Bristol, in the county of Hartford and State of Connecticut, have invented a new, original, and ornamental Design for a Clothespin or the like, of which the following is a specification, reference being had to the accompanying drawing, forming part thereof.

Figure 1 is a perspective view of a clothespin or the like showing my new design. Figure 2 is a side view thereof and Figure 3 is an edge view.

I claim:

The ornamental design for a clothespin or the like, as shown.

HARRY M. BROADWELL.
